ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

KNIT FABRIC HAVING THICKENED WALES.

1,267,126.

Specification of Letters Patent. Patented May 21, 1918.

Application filed August 1, 1916. Serial No. 112,592.

To all whom it may concern:

Be it known that I, ROBERT W. SCOTT, a citizen of the United States, and resident of Boston, in the county of Suffolk and State of Massachusetts, have invented new and useful Improvements in Knit Fabrics Having Thickened Wales, of which the following is a specification.

This invention relates to the manufacture of thickened wale structures in knit fabrics. Objects of the invention are to provide for hosiery, gloves or other knit articles or fabrics an element of ornament or use consisting of isolated, raised or thickened wales which lend themselves well to the formation of clock effects and mock-seams in hosiery and underwear, ridges on the backs of gloves, and the like; and to provide for the manufacture of fabrics having such thickened wales upon the usual instruments, without interfering with the steps employed for making ordinary fabrics. Further objects are to provide a structure of this nature adapted for machine-knit fabrics and capable of being begun and ended at any desired parts of the knit article without interference with the making of the article or the operation of the machine, and to provide a knit structure for this purpose which shall be relatively opaque and dense and which does not weaken the fabric to which it is applied, as well as a method of making said structure. Heretofore twisted or tucked stitches have been employed for some of the uses to which my new fabric is adapted, but such structures necessarily contain fewer stitches or stitches under more strain than the body of the fabric, and for these reasons are weaker under longitudinal stress than the remainder of the fabric. Such structures are little or no thicker than the fabric to which they are applied, and are nearly as transparent as the body fabric, so that a thick or opaque mark in a transparent fabric does not result from their employment. For the above and other purposes my present invention comprises applying to a fabric and interknitting therewith an additional continuous yarn.

In the accompanying drawings,

Figure 1 is a diagram showing a back or inside view of a fabric provided with one form of the new structure;

Fig. 2 is a similar view illustrating intermittently thickened wales for close imitation of a looper-sewed seam;

Fig. 3 is a similar view showing a single thickened wale;

Fig. 4 similarly shows an intermittent form of the structure of Fig. 3;

Fig. 5 is a view of a stocking containing the new structure;

Fig. 6 is a diagram in plan of a circle of knitting needles illustrating one manner of placing the thickening yarn for interknitting with the fabric;

Figs. 7 and 8 are diagrams in plan showing the relation of the thickening yarn to certain needles;

Fig. 9 is a diagram development showing one series of movements of such knitting needles coöoperating with guides for the body and thickening yarns; and

Fig. 10 shows normal needles and special needles adapted to form a larger knit loop.

For an illustrative instance, referring to Figs. 1 and 5, a section 1 of knit fabric, such as the back of the leg fabric or any other desired part of a tubular stocking S, is provided with a longitudinal thickened mock-seam, mark or ridge 2. In the position shown the mock-seam 2 imitates a looper seam characteristic of flat-fashion hosiery.

As shown in Fig. 1, certain wales b of the fabric 1, in addition to the yarn k of which the fabric is composed, include an auxiliary thickening yarn t connecting two or more wales b and floated between them in floats y, y' on the back or inside face of the fabric. One or more normal wales a' may intervene between the wales b, and the floats y, y' may be under any desired tension, the presence of the floats projecting the intervening wale or wales a' in a ridge on the face side of the fabric. The yarn t as shown in Fig. 1 is interknit with itself and accompanies the structural yarn k in each wale b, the floats y extending from loop to loop in the same course, and the floats y' extending

from a loop of one wale b in one course to a loop of the other wale b in the next following course. The wales b preferably are formed of longer stitches than wales a .

5 I prefer to form the seam 2 as follows: Assuming as the instrument of manufacture a movable latch-needle knitting machine, the knitting yarn k may be formed into the fabric 1 as usual by a wave w' , w , 10 Fig. 9, of advance and retraction in the needles, the body-yarn k supplied by a yarn-guide k' being taken in the hooks of the needles n during their retraction, as shown after their partial retraction at w^s and before their complete retraction. Laying the thickening yarn t on the needles n' , n' knitting the wales b , in addition to the yarn k is now provided for, so as to take the yarn t into the hooks of these needles prior to 20 their retraction at w . For this purpose needles n' , n' are isolated from the other needles to enable them to receive yarn t . The method of distributing the yarn t for this result is independent of the particular 25 means for knitting or for isolating the said needles. The yarn t may be of any suitable color or kind. To accommodate the yarn t in stitches also containing the body-yarn and in some cases as explained below a third 30 yarn, the needles n' for the wales b may be formed as shown in Fig. 10, so that the distance from their butts to their hooks is less than that of the needles n .

One procedure comprises winding or 35 wrapping the yarn t continuously in one direction about the isolated needle or needles n' , n' . To produce the fabric shown in Fig. 1, the operation includes thereafter arranging that run y' of the wrapped yarn 40 lying on the face or hook side of separated needles n' , n' , behind the backs of the intervening normally-knitting needle or needles forming wale a' , as needle n^s in Fig. 7. One way of doing this is to permit the rotation of the needle group n' , n^s , n' relatively 45 to the needle cams and the yarn-feed devices to wrap the yarn t about needles n' , n' while these needles are elevated above their neighbors, and thereafter to move the 50 needles into a normal position in line with needle n^s and the remaining needles n , the form, arrangement or position of the needle or needles n^s and the needles n' being such as to secure passage of the float y behind 55 the needles n^s . Referring to Figs. 6, 7, and 8, Fig. 6 is a diagram showing four positions in one relative revolution of a needle n' representative of the group n' , n^s , n' with respect to yarn guide t' for the yarn t . 60 It will be observed that yarn t if free to take any position across the circle of needles n will virtually be rotated with respect to any narrow group of needles, as n' , n^s , n' , or a single needle n' as illustrated by ar-

rows d , Figs. 7 and 8, in a direction contrary to the rotation of the needles relative to the yarn guide in direction a . Either the needles or the yarn guide may be on the movable part of the machine.

The needles n' , n' may be projected or 70 otherwise isolated at any part of their rotation to receive the auxiliary yarn while passing yarn guide t' positioned in any desired relation to the knitting cams or other active knitting devices.

75 The effective rotation around the isolated needles of the yarn t indicated in Figs. 6, 7, and 8 will not be interrupted if these needles are retracted to knit, or to arrange the yarn t behind intervening needles, at 80 any part of the circle swept by the needles sufficiently separated from the yarn-guide to secure first having brought the yarn t above and within the circle of needles n , in the position of a chord of the circle n . The 85 yarn t may be fed through any usual yarn take-up device permitting the yarn drawn off by the receding needle n' to be recovered at the approaching passage through the remainder of the rotation of the needle n' 90 and yarn guide t' .

95 One convenient arrangement of relative movements for laying the yarn t is illustrated in Fig. 9. All the needles are advanced at w' and the needles n' , n' may be 100 permitted to retain all or a part of this advance, as at w^s (for instance by providing them with shorter butts than the other needles and by employing a cam formed to partially retract the other needles n , n^s , as by 105 having a cut away portion upon which the needles n' , n' enter) so that at this point they stand above the other needles. Yarn guide t' , which may be movable, delivers the yarn t at this point above the height 110 of the normal needles n , n^s . The needles n , n^s , which may be provided with the usual forward hooks standing in front of the front faces of their shanks, will upon passage at w come into alignment. The needle 115 n^s here passes in front of yarn t , Fig. 7, all the needles t receiving the main yarn k , and knitting on full retraction. Needles n' then have in their hooks both yarn k and 120 yarn t , and on their shanks loops of both yarns, whereby to form the double-loop structure of wales b .

125 The needles n' , n' may in some cases be normal needles, but sufficiently separated by not being adjacent needles to permit leading needle n' to knit and advance before the following needle n' is retracted to its maximum. This permits the wrapped yarn t safely to be knitted without breakage without special provision for the double-yarn stitches, and 125 while maintaining tension on the floats y , y' . It will be understood, however, that several needles n' may be arranged side by side when

provision is made for elongating their stitches, as above explained, or by other suitable means.

The formation of the thickened place or seam 2 may be begun and ended at desired predetermined points by moving the yarn guide t' into and out of operative position, the different movement of the needles n', n' having no effect on their normal operation to knit yarn k , or the needle movement may be altered by changing the form of the cam path, as by providing movable cams.

In some cases I prefer to intermit forming the thickened wales at one or more courses w' at intervals of a few courses apart, as shown in Fig. 2, to impart a puckered appearance to the mock-seam 2. This may be done either by suspension of feeding of the yarn t or by causing the needles n' to be normally operated when passing the seaming yarn guide during knitting the course w' . In either case the yarn t forms a run r at the back of the fabric until the needles or the auxiliary yarn guide t' are again positioned to cause needles n' to take yarn t .

My invention comprises fabrics having a thickened mark only one needle-wale wide, which may as shown at b' in Fig. 3 be continuous between beginning and end, or be intermitted, as shown in the course w'' with respect to the wale b'' in Fig. 4. In these cases, a single needle n' will be utilized as above-described, the yarn t being wrapped about it by isolating the needle, as at w^2 , Fig. 9, and by the relative rotation illustrated in Fig. 6, the method being otherwise the same as above.

The described structure is well adapted to be formed in a stocking S having one or more spliced areas, as the high splice h shown above the heel in Fig. 5. As well known to those skilled in the art, such spliced areas as the area h are formed of the body-yarn k and an additional yarn s , Figs. 1, 3 and 4. There is little or no room in a knit loop of the usual texture for this additional yarn, and it is customary and usually necessary to increase the length of stitch at such portions of the fabric as are spliced by the addition of the yarn s . My new structure, in each of its forms, but as specifically illustrated in Figs. 1, 3 and 4 only, is adapted to be made in or through such a spliced area by increasing the length of stitch in wales b as above described, in order to permit the double yarn stitches of this area to accommodate a knit loop of the third yarn s .

It will be observed that the needles n' for the wales b are among those to which the splicing yarn s is applied, by which arrangement the needles n' are always permitted to pass the splicing yarn guide of the usual machine arrangements when splicing is be-

ing done, without the float, extending across the circle, of the yarn t encountering the float of the yarn s , the yarn s then being withdrawn by the splicing device from the needles which are not to receive it to float diametrically across the circle at a time the needles n' are in a part of the circle at which the float of yarn t can not encounter the float of the splicing yarn s . When the splicing yarn s is finally withdrawn, it is as usual cut and clamped leaving the yarn t free to make the described movements.

Wherever the additional yarn t is interknit with body or splicing yarn, the body yarn preferably is in plating relation to the additional yarn, which appears on the back or inside face only of the fabric.

I do not herein claim the invention common to this application and my application Serial No. 112,591, filed August 1, 1916, [Letters Patent No. 1,256,834, granted February 19, 1918,] claiming the genus of which the present disclosure is one species.

What I claim is:

1. A knit fabric formed of a body-yarn having therein two spaced needle wales only connected by an additional thickening yarn free from engagement with one or more intervening wales and alternately interknit with the body-yarn in one and in another of said spaced wales, whereby to form a thickened longitudinal mark, an intervening wale of the body fabric being projected in a ridge on the face side of the fabric.

2. A knit fabric formed of a body-yarn and having therein a longitudinal mark or ridge comprising wales of knit loops consisting of the body-yarn and a continuous additional yarn, said yarns being in plating relation in said wales, and floating between said wales in tensioned floats on one face of the fabric only, the tension on said floats being sufficient to project the face of the fabric from the body at said wales.

3. A knit fabric formed of a body-yarn having therein a longitudinal mark or ridge comprising wales of elongated or slackened knit loops each consisting of the body-yarn and a continuous additional yarn, said wales being connected by floats under tension, whereby to project a part of the body-fabric from the face thereof.

4. A knit fabric formed of a body-yarn having therein a longitudinal mark or ridge comprising wales of elongated or slackened knit loops each consisting of the body-yarn and a continuous additional yarn in plating relation thereto, tensioned floats of said additional yarn extending in opposite directions from wale to wale at the back of the fabric.

5. A knit fabric formed of a body-yarn having a longitudinal thickened mark projecting from one face of the fabric comprising needle-wales of the body-yarn in-

terknit with an additional yarn extending in tensioned floats from wale to wale on the other face of the fabric, the tension being sufficient to project the face of the fabric 5 from the body at said wales.

6. A knit fabric formed of a body-yarn having a longitudinal thickened mark projecting from one face of the fabric comprising needle wales in which there are knit 10 loops of the body-yarn and an additional

yarn, said additional yarn extending in tensioned floats from wale to wale on the other face of the fabric, said additional yarn at predetermined intervals being floated over an intervening course without being inter- 15 knit.

Signed by me at Boston, Massachusetts, this twenty ninth day of July, 1916.

ROBERT W. SCOTT.
